UNITED STATES PATENT OFFICE.

ORLA E. JUVINALL, OF DANVILLE, ILLINOIS.

ARTIFICIAL BAIT CARRIER.

Application filed October 3, 1925. Serial No. 60,231.

This invention relates to an artificial bait carrier, and the object of the invention is the construction of a simple and efficient carrier that can be rolled into a compact form or 5 shape, and which is adapted to carry artificial bait in pockets; the number of pockets being entirely optional with the owner or user of the carrier.

Another object of the invention is the construction of a simple and efficient bait carrier, made, preferably, of flexible material such as leather, and which comprises a body having one pocket, to which one or more additional detachable pockets or sections 15 may be quickly attached or added.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a front plan view of another embodiment of my bait carrier.

Figure 2 is a sectional view taken on line 5—5, Figure 4 and looking in the direction of the arrows.

Figure 3 is a rear plan view of the bait carrier shown in Figure 1, with one of the pocket sections removed.

Referring to the drawings by numerals, 1 designates an elongated flexible body that may be constructed from a single strip of 35 material such as leather, and which has its edges reinforced by turned over strips 2, both at its sides and ends. An elongated flexible body having reinforcing strips 2, and extending through one of the strips 2 is an eye 4, through which is threaded a tying string 5, which when the carrier is rolled, is used to tie the carrier in its rolled condition, for storing or transportation purposes.

In each pocket 3 and 3^a is carried a separate bait; that is, one kind of artificial bait can be carried in one pocket and another kind in another pocket, and as is shown, as many pockets can be used or added to the carrier as is necessary to accommodate as many 50 kinds of bait as are desired.

Each pocket 3 is closed at its ends and bottom and is open at its top. In the embodiment (Fig. 4) I have shown only one pocket 3 permanently attached to body 1, for the user may only want a carrier with 55 one pocket, but the carrier is more efficient

with a plurality of pockets 3^a, and I have illustrated a novel method of adding pockets 3^a to the carrier as additional kinds of bait are contemplated or used. The adding of 60 these detachable pockets 3^a is accomplished by fastening one end of a plurality of receiving tabs 6 to the lower portion of each pocket 3^a, and to the inner face of each pocket, and at its upper edge, I fasten the 65 inner end of anchor tabs 7; it is to be understood that the receiving tabs and anchor tabs are both fastened to the back or inner face of the pockets 3^a. Further, there is a set of receiving tabs 6 fastened to the lower 70 part, and the inner face of the body 1 at pocket 3; these tabs 6 that are fastened to body 1, depending from the body, as shown in the drawings.

Each receiving tab is provided with a 75 transversely extending elongated slot 8, into which slots 8 are inserted the arrowhead-like ends 9 of the anchor tabs 7. When these arrowheads are in the slotted receiving tabs 6, the section or sections will be 80 efficiently fastened together, and can not be easily separated, only when the operator desires. By placing a series (three shown in the drawings) of receiving tabs and anchor tabs on the device, in a row or in alignment, the centers of the pockets are kept 85 from "buckling" or puckering, which is of importance and possesses advantage in allowing the sectional bait carrier to be rolled up into a compact form or bundle, 90 and then tied in its rolled or closed position by the string 5.

As hereinbefore suggested, as the operator needs a new section to accommodate a new or added bait to his collection, a 95 section can be added with ease and rapidity, and by reason of all the structure being of flexible material such as leather, the entire device, when rolled or folded, will require comparatively little space for storage. It is also to be noted that I have preferably provided a receiving tab and an anchor tab near each end of each pocket-section, as 100 well as at the center, for the purpose hereinbefore specified.

While I have described the preferred embodiment of my invention and illustrated the same in the accompanying drawings, certain minor changes or alterations may appear to one skilled in the art to which this 110 invention relates, during the extensive manufacture of the same, and I, therefore,

reserve the right to make such alterations or changes as shall fairly fall within the scope of the appended claims.

It is to be understood that the receiving tabs 6 and the anchor tabs 7 constitute interlocking means, as well as lacing means for detachably securing the sections of the device together in the specific and peculiar manner hereinbefore specified.

10 What I claim is:

1. In a device of the class described, the combination of a body provided with receiving tabs, a pocket provided with anchor tabs, and said anchor tabs adapted to interlock with said receiving tabs for fastening said pocket to said body.
- 15 2. In a device of the class described, the combination of a body provided with a plu-

rality of depending slotted tabs, a pocket-section provided with a plurality of extending anchor tabs, and said anchor tabs adapted to extend through the slotted tabs for fastening said pocket-section to said body.

3. In a device of the class described, the combination of a body provided at one end with a central and end depending receiving tabs, each receiving tab provided with transverse elongated slots, a pocket-section provided with a central and end extending anchor tabs, each anchor tab provided with an arrowhead-like end, and said arrowhead-like ends extending through said slots for fastening said pocket-section to said body.

In testimony whereof I hereunto affix my signature.

ORLA E. JUVINALL.
